UNITED STATES PATENT OFFICE.

HORACE G. RICHARDSON, OF SAN ANTONIO, TEXAS.

ASPHALT SPREADER.

Application filed September 18, 1925, Serial No. 57,187. Renewed March 28, 1927.

This invention relates to new and useful improvements in spreading devices and particularly to devices for spreading material on streets, such as asphalt, stones, sand, or the like paving materials.

One object of the invention is to provide a device of this character which is adapted to be connected to the rear end of a wagon, whereby, upon tilting the box of the wagon, 10 in the act of dumping the load, such material will be evenly spread on the surface of the street or road.

Another object is to provide a device of this character by means of which the material may be spread to the desired or required thickness, the device being readily adjustable to permit variations in the thickness of the stream of material issuing from the wagon.

20 Other objects and advantages will be apparent from the following description when taken in connection with the accompanying drawings.

In the drawings:

25 Figure 1 is a side elevation of a wagon, in dumping position, and equipped with the present invention.

Figure 2 is a top plan view of the same.

30 Figure 3 is a rear elevation of the same.

Figure 4 is a vertical longitudinal central sectional view on the line 4—4 of Figure 2.

Referring particularly to the accompanying drawings, 10 represents a wagon which includes the dumping body or box 11, in connection with which the present invention is adapted for use.

35 Mounted on the rear end of the wagon box is a box 12, the upper and rear portions of which are open, as clearly seen in the drawings, and particularly in Figure 4. Mounted in the upper rear portion of the box is a transverse bar 13, on which is movably mounted a downwardly and rearwardly inclined baffle 14, which is arranged to rest on the upper surface of the asphalt as such asphalt flows from the wagon box into the box 12. The lower free edge portion of this baffle plate is formed with the series of regularly spaced teeth 15, between which are disposed the grate bars 16. These grate bars are carried by a transverse shaft 17, disposed below the bottom of the box 12, and have their lower ends in position to hold back the asphalt. The portion of the box 12, 50 forwardly of the grate 16, is, in effect, a hopper, while that portion to the rear of the

grate performs the function of a discharging chute for the asphalt. Extending upwardly from the center of the bar 17 of the grate bars 16 is a lever 18, and pivotally connected 60 to the free end of this lever is a link 19, which extends rearwardly and is provided with a series of ratchet teeth 20, for engagement with the transverse bar 21, whereby to accomplish the rocking of the grate bars toward and away from the asphalt.

One object of the invention is to provide a device of this character which is adapted to be connected to the rear end of a wagon, whereby, upon tilting the box of the wagon, 10 in the act of dumping the load, such material will be evenly spread on the surface of the street or road.

Another object is to provide a device of this character by means of which the material may be spread to the desired or required thickness, the device being readily adjustable to permit variations in the thickness of the stream of material issuing from the wagon.

20 Other objects and advantages will be apparent from the following description when taken in connection with the accompanying drawings.

In the drawings:

25 Figure 1 is a side elevation of a wagon, in dumping position, and equipped with the present invention.

Figure 2 is a top plan view of the same.

30 Figure 3 is a rear elevation of the same.

Figure 4 is a vertical longitudinal central sectional view on the line 4—4 of Figure 2.

Referring particularly to the accompanying drawings, 10 represents a wagon which includes the dumping body or box 11, in connection with which the present invention is adapted for use.

35 Mounted on the rear end of the wagon box is a box 12, the upper and rear portions of which are open, as clearly seen in the drawings, and particularly in Figure 4. Mounted in the upper rear portion of the box is a transverse bar 13, on which is movably mounted a downwardly and rearwardly inclined baffle 14, which is arranged to rest on the upper surface of the asphalt as such asphalt flows from the wagon box into the box 12. The lower free edge portion of this baffle plate is formed with the series of regularly spaced teeth 15, between which are disposed the grate bars 16. These grate bars are carried by a transverse shaft 17, disposed below the bottom of the box 12, and have their lower ends in position to hold back the asphalt. The portion of the box 12, forwardly of the grate 16, is, in effect, a hopper, while that portion to the rear of the

grate performs the function of a discharging chute for the asphalt. Extending upwardly from the center of the bar 17 of the grate bars 16 is a lever 18, and pivotally connected 60 to the free end of this lever is a link 19, which extends rearwardly and is provided with a series of ratchet teeth 20, for engagement with the transverse bar 21, whereby to accomplish the rocking of the grate bars toward and away from the asphalt.

Mounted transversely in the chute portion of the box 12, immediately in rear of the grate bars 16, is a shaft 22, and fixed on this shaft are the plurality of radially extending raker arms 23, which play between the teeth or grate bars 16, to draw the asphalt from the load into the discharging chute portion. By the adjustment of the grate bars forwardly and rearwardly, the raker arms can 70 dig into the asphalt, between said bars, to greater or lesser degrees, whereby to regulate the amount of asphalt to be drawn from the hopper portion of the box. The ends of the shaft 22 project to suitable distances beyond the sides of the hopper, and mounted on these ends are the gears 24. Similarly mounted in the sides of the chute portion of the box 12, rearwardly of the shaft 22, is a shaft 25, and secured to this shaft, and extending radially therefrom, are the longitudinally extending spreader bars or blades 26. On the ends of the shaft 25, which project through the sides of the chute portion, are the gears 27. Mounted on the shafts 22, 80 carried by the sides of the hopper, intermediate the projecting ends of the shafts 22 and 25, are the internally toothed wheels 29, which engage with the gears 24 and 27, to simultaneously drive the shafts 22 and 25. 90

As clearly seen in Figure 1, when the wagon box is tilted into dumping position, the asphalt will run down against the grate bars 16, and the wheels 29 engage on the ground. As the wagon is pulled forwardly, in this position, the wheels 29 will drive the shafts 22 and 25, so that the raker arms will drag the asphalt from the load, through the grate bars, from the hopper into the chute portion, where it is moved along by the spreader bars or blades 26, and out onto the road or street surface.

By adjusting the grate bars toward or away from the raker arms, such arms will pass between the bars to greater or lesser degrees, thereby raking out more or less of the asphalt, with the result that the asphalt

will be delivered to the spreader bars in greater or lesser quantities, thereby regulating the thickness of the asphalt spread onto the road surface.

5. What is claimed is:

1. An asphalt spreading device comprising a receptacle for containing asphalt, a vertically slotted plate against which the load of asphalt rests, a rotary raker mounted in 10 position to rake the asphalt through the slots of the plate, means for discharging and spreading, onto a street surface, the material thus raked, and means for moving the slotted plate toward and away from the raker, 15 whereby to permit the latter to move through the slots to greater or lesser degrees and thereby regulate the amount of asphalt fed to the discharging and spreading means.
2. An asphalt spreading device comprising 20 an inclined dumping receptacle, ground wheels supporting the lower end of the receptacle, a vertical plate movably mounted transversely in the receptacle and arranged to receive the load of asphalt thereagainst, 25 said plate having openings therein, a raker driven by the ground wheels and movable through said openings to draw asphalt there-through, means below the raker for moving

the asphalt out onto a street surface, and means for moving the vertical plate whereby 30 to regulate the depth to which the raker enters the load of asphalt and the amount thereof drawn out by the raker.

3. An asphalt spreading device including an inclined receptacle, a transverse baffle plate 35 against which the load of asphalt rests, said plate being pivotally connected to the lower portion of the receptacle and having vertical slots therein, wheels supporting the receptacle, a rotary raking device driven by the 40 ground wheels and having teeth moving through the slots of the plate to draw asphalt through said slots, rotary means for receiving the asphalt thus raked through the slots and discharging same onto a street surface, a plate movably mounted in the receptacle and having projections engaged in said 45 slots for directing the asphalt toward the slots, and means for adjusting the slotted plate toward and away from the raker whereby to permit the raker to dig to different depths into the asphalt through said slots.

In testimony whereof I affix my signature.

HORACE G. RICHARDSON.
